UNITED STATES PATENT OFFICE.

ANTON METTLER, OF REICHENBURG, SWITZERLAND.

DEVICE FOR SINGEING THREADS.

Application filed March 12, 1926, Serial No. 94,265, and in Switzerland April 9, 1925.

This invention refers to improvements in devices for singeing threads of any kind and particularly to an insertion piece for gas singeing chambers, of the type, which are 5 provided with a tubular member through which the thread to be singed passes in the longitudinal direction and which together with an outer wall defines a gas distributing chamber from which the combustible gas 10 flows into the interior of the tubular member.

According to the present invention the wall of the tubular member is weakened, i. e., kept thinner on a portion of the circumference of the said member whereby the recess on the circumference of the member which causes the weakening of the wall forms a gas distributing chamber and the 15 weakened wall forms a glowing surface.

20 The glowing surface essentially assists the singeing action and a tubular member or burner tube of this type may be inserted into existing singeing apparatus of the known type for better utilizing the heating power 25 of the gas.

Preferably the tubular member is provided in its weakened part with longitudinal slots arranged diametrically opposite each other through which the combustible gas passes so 30 that two flames pointing towards each other and completely surrounding the thread to be treated are obtained and the ends of the tubular member are conically enlarged to facilitate the escape of the combustion residues 35 from the tubular member.

Constructional examples of the subject matter of the present invention are illustrated on the accompanying drawings, in which:

40 Fig. 1 is an outside view of the tubular member,

Fig. 2 is a longitudinal section and

Fig. 3 is a cross-section along line III—III of Fig. 1.

45 Fig. 4 shows in a longitudinal section the tubular member inserted in a singeing chamber.

Fig. 5 is an outside view of an additional tube to be inserted in the tubular member,

50 Fig. 6 is a cross-section of the additional tube,

Fig. 7 shows in a longitudinal section the singeing chamber, the tubular member and the additional tube,

55 Fig. 8 is a cross-section along line VIII—VIII in Fig. 7,

Fig. 9 is a cross-section corresponding to that shown in Fig. 8, the additional tube, however, occupying a different angular position,

60 Fig. 10 is an elevation of a general arrangement of a singeing apparatus and

Fig. 11 is an end view of Fig. 10.

Referring now to the drawings 1 denotes a metallic tubular member, consisting for instance, of steel, and having a wall that is over part of the circumference considerably reduced in thickness so that a thin glowing wall 2 is formed. The glowing wall 2 of the member 1 serves together with the tube A 70 forming the singeing chamber to define the gas distributing chamber 3 to which a combustible gas is supplied by the conduit 4 as is shown in Fig. 4. In the glowing wall 2 the tubular member 1 is provided with two 75 longitudinal slots 5 arranged diametrically opposite each other and through which the gas enters the interior of the tubular member 1 to burn in two flames pointing towards each other. The tubular member 1 is further provided with a longitudinal slot 6 permitting the thread B to be introduced to which end the tube A is also provided with a longitudinal slot registering with the slot 6. On account of the slot 6 the tubular member 1 is 80 held by clamping action in its position inside the tube A. It is evident that the glowing wall 2 in which the slots 5 for the gas are provided will materially increase the singeing action.

90 Further a closed groove 7 is provided adapted to take up a strip of packing material in order to pack the gas distributing chamber gas tight along its circumference. The interior of the tubular member 1 is 95 conically enlarged at both ends 23 in order to facilitate the removal of the residues of combustion.

The additional metallic tube or control member 8 illustrated in Figs. 5-9 and consisting for instance of steel, is provided with two longitudinal slots 9 arranged diametrically opposite each other and having an enlarged portion 10 at both ends. The tube 8 is further provided with a longitudinal 100 slot 13 so that it is held in its position in the tubular member 1 by clamping action. At both ends the tube 8 is provided with notches 11 adapted to receive a tool, for instance a screw driver, by means of which the angular 105 position of the tube 8 inserted in the tubular member 1 may be so adjusted with regard to

the latter by turning the tube 8 that its slots 9 may register with the slots 5 of the tubular member 1 as is shown in Fig. 8 or that the slots 5 are partly closed, as is shown in Fig. 9. The latter is the case if the enlarged parts 10 of the slots 9 only permit a passage of the gas whilst the part of the slots 9 between the enlarged parts 10 does not register with the slots 5 of the tubular member 1. In this manner the slots 5 of the tubular member 1 are closed to some extent and the gas passes through the slots 5 of the tubular member 1 only as far as the enlarged parts extend so that a correspondingly weaker flame is produced as is necessary when treating certain yarns or threads.

The tubular member 1 may also be inserted in other bodies forming singeing chambers instead of in a singeing tube A.

In the general arrangement illustrated in Figs. 10 and 11 a plurality of singeing tubes A are arranged one beside the other on a frame 14 and the threads B are unwound by the conduit 4 and the combustion residues are removed by the action of the suction fan 17 for which purpose the upper ends of the singeing tubes A are connected by the branches 18 and the conduit 19. The singed thread passes over guides 20 to a winding device 21 and is wound on reels 22.

I claim:

1. In a device for singeing threads by means of a combustible gas, a tubular member having part of its wall thinned to form a glowing wall, longitudinal slots being arranged diametrically opposite each other in said thin part of the wall to permit the combustible gas to pass into the interior of the tubular member.

2. A device for singeing threads by means of a combustible gas, comprising in combination, a singeing chamber, a tubular member inserted in said singeing chamber and having part of its wall thinned to form a glowing wall, said thinning being caused by a recess in the outer circumference of the tubular member, and said recess and the juxtaposed part of the wall of said singeing chamber forming a distributing chamber for the combustible gas to be supplied to said chamber, longitudinal slots being arranged diametrically opposite each other in said weakened part of the wall to permit the combustible gas to pass into the interior of the tubular member.

3. A device for singeing threads by means of a combustible gas, comprising in combination, a singeing chamber, a tubular member inserted in said singeing chamber and having part of its wall thinned to form a glowing wall, and both ends of said tubular mem-

ber being conically enlarged, said thinning being caused by a recess in the outer circumference of the tubular member and said recess and the juxtaposed part of the wall of said singeing chamber forming a distributing chamber for the combustible gas to be supplied to said chamber, longitudinal slots being arranged diametrically opposite each other in said weakened part of the wall to permit the combustible gas to pass into the interior of the tubular member.

4. A device for singeing threads by means of a combustible gas, comprising in combination a singeing chamber, a tubular member inserted in said singeing chamber and having part of its wall thinned to form a glowing wall, and both ends of said tubular member being conically enlarged, and a continuous groove being formed in the outer circumference of said tubular member and encircling said weakened part of the wall, a packing strip inserted in said groove to pack the tubular member in a gas-tight manner against said singeing chamber, said thinning being caused by a recess in the outer circumference of the tubular member and said recess and the juxtaposed part of the wall of said singeing chamber forming a distributing chamber, longitudinal slots being arranged diametrically opposite each other in said weakened part of the wall to permit the combustible gas to pass into the interior of the tubular member.

5. A device for singeing threads by means of a combustible gas, comprising in combination, a singeing chamber, a tubular member inserted in said singeing chamber and having part of its wall thinned to form a glowing wall, said thinning being caused by a recess in the outer circumference of the tubular member and said recess and the juxtaposed part of the wall of said singeing chamber forming a distributing chamber for the combustible gas to be supplied to said chamber, longitudinal slots being arranged diametrically opposite each other in said weakened part of the wall to permit the combustible gas to pass into the interior of the tubular member, and an additional tube inserted in said tubular member and provided with slots and adapted to be angularly displaced relatively to said tubular member for regulating the areas through which the gas passes into the tubular member.

6. In a thread singeing device, a tubular member having a slot throughout its length and gas slots, the wall of said member including said gas slots being thinner than the remaining portion of the member.

7. In a thread singeing device, a longitudinally slotted, gas heated, tubular member having a thin wall portion capable of being heated to glowing and a packing groove surrounding said wall.

8. In a thread singeing device, a tubular

member having a slot throughout its length and diametrically opposite gas slots, and means to control the passage of gas through the slot from outside of said wall.

- 5 9. In a thread singeing device, a tubular member having a slot throughout its length and substantially diametrically opposite gas slots, and means within said member to control said slots.
- 10 10. In a thread singeing device, a tubular member having a slot throughout its length and substantially diametrically opposite gas slots, and an additional tubular member having slots registrable with the aforesaid slots, the slots in said additional member registering with the gas slots having enlarged ends.
- 15 11. In a thread singeing device, a detachable tubular member having a slot throughout its length and substantially diametrically opposite gas slots; and an additional tubular member having a slot also extending throughout its length for registration with the first mentioned slot, gas slots registrable with the aforesaid gas slots and frictionally held within the first for rotatable adjustment therein.
- 20 12. In a thread singeing device, a tube having a slot throughout its length and a gas supply pipe connected thereto between its ends, a detachable tubular member frictionally held therein and having a slot throughout its length and registrable with the aforementioned slot, a portion of the wall thereof thinned to form a glowing wall, and gas slots disposed longitudinally in said thinned portion, said thinned portion being arranged opposite said gas supply pipe and forming a gas chamber between the tube and member.
- 25 13. In a thread singeing device, a tube

having a slot throughout its length and a gas supply pipe connected thereto between its ends, a detachable tubular member frictionally held therein and having a slot throughout its length and registrable with the aforementioned slot, a portion of the wall thereof thinned to form a glowing wall, and gas slots disposed longitudinally in said thinned portion, said thinned portion being arranged opposite said gas supply pipe and forming a gas chamber between the tube and member, and said member having its bore conically enlarged at both ends.

14. In a thread singeing device, a tubular gas control member having a slot throughout its length and substantially diametrically arranged slots enlarged at their ends.

15. In a thread singeing device, a tubular gas control member longitudinally split and having diametrically opposite slots each enlarged peripherally in opposite directions at the ends, and spanner notches in the ends of the member.

16. In a thread singeing device, an outer tube having a longitudinal thread inserting slot, and a separate tube therein, having a similar slot registering with the first slot, said latter tube having an external reduced diameter between its ends to form a gas chamber between it and the inner wall of the outer tube and form a wall sufficiently thin to glow and gas exit openings in the thinned portion of the inner tube and means to supply gas to the chamber between the tubes.

In testimony whereof, I have signed my name to this specification.

ANTON METTLER.
